SMOKER'S ACCESSORY TRAY

William C. Wayman, 512 S. Oak Park Ave.,
Oak Park, Ill.

Filed Aug. 29, 1963, Ser. No. 76,390

Term of patent 14 years

(Cl. D85—2)

Fig. 1

Fig. 2

Fig. 4

FIG. 2 is a top plan view of the same;

FIG. 3 is a side view of the same, looking at the left hand side of FIG. 2; and

FIG. 4 is a fragmentary sectional view taken on the section line 4—4 of FIG. 2.

The side not shown is plain and unornamented.

I claim:

The ornamental design for a smoker's accessory tray, substantially as shown and described.
